GRINDING MACHINE-TABLE RECIPROCATING MECHANISM

John I. Garside, West Boylston, Mass., assignor to
 Norton Company, Worcester, Mass., a corpora-
 tion of Massachusetts

Application May 14, 1940, Serial No. 335,111

9 Claims. (Cl. 121—45)

The invention relates to grinding machines, and more particularly to a hydraulically operated table reciprocating mechanism for a grinding machine.

One object of the invention is to provide a simple and thoroughly practical hydraulically operated table reciprocating and reversing mechanism. Another object of the invention is to provide a table reversing mechanism with an improved dwell control mechanism. A further object of the invention is to provide a hydraulically operated table reversing mechanism with a variable dwell control whereby a variable dwell may be obtained at the ends of the table reciprocation.

A further object of the invention is to provide an electrically controlled dwell control for the hydraulically operated table reciprocating mechanism. A further object of the invention is to provide a hydraulically operated table reciprocating mechanism with an electrical time delay relay control for a hydraulically operated dwell control to control the extent of dwell at each end of the table stroke.

A further object of the invention is to provide a dwell control mechanism in which the table movement serves to shift a control or reversing lever to a central or neutral position and a time delay mechanism serves to control the admission of fluid under pressure to complete the reversal of said valve. Other objects will be in part obvious or in part pointed out hereinafter.

The invention accordingly consists in the features of construction, combinations of elements, and arrangements of parts, as will be exemplified in the structure to be hereinafter described, and the scope of the application of which will be indicated in the following claims.

In the accompanying drawings, in which is shown one of various possible embodiments of the mechanical features of this invention,

Fig. 1 is a combined hydraulic and electric diagram of the improved table reciprocating mechanism;

Fig. 2 is a cross sectional view through the table reciprocating mechanism, showing the reversing lever, reversing valve and the parts actuated by said lever;

Fig. 3 is a fragmentary elevation showing the arrangement of the reversing valve and the dwell control switches which are actuated by movement of the table reversing lever;

Fig. 4 is a cross sectional view, on an enlarged scale, through the manually operable table traversing mechanism;

Fig. 5 is a fragmentary sectional view, taken approximately on the line 5—5 of Fig. 4; and

Fig. 6 is a fragmentary sectional view taken approximately on the line 6—6 of Fig. 4.

As illustrated in the drawings, the machine embodying this invention comprises a base 10 which supports a longitudinally reciprocable table 11 on the usual V-way (not shown) and flat way 9 for a longitudinal reciprocatory movement relative to the base 10.

A fluid pressure operated reciprocating mechanism is provided to reciprocate the table 11 comprising a fluid pressure cylinder 12 which is fixedly mounted on the under side of the table 11. The cylinder 12 is provided with a pair of spaced pistons 13 and 14 which are connected by a pair of hollow piston rods 15 and 16, respectively, with a pair of hollow brackets 17 and 18, respectively, mounted on opposite ends 20 of the base 10.

In the preferred construction the base 10 is formed with a hollow, box-like construction in which the lower portion forms a reservoir 20 through a pipe 21 by a motor driven fluid pressure pump 22 which forces the fluid through a pipe 23 and a pipe or passage 24 to a table control valve 25. An adjustable fluid pressure relief valve 26 is provided in the pipe line 23 and is arranged to allow excess fluid under pressure to by-pass through a pipe 27 into the reservoir 20 in case pressure within the system increases above a desired and predetermined pressure.

The table control or reversing valve 25 is preferably a piston type reversing valve which includes a valve stem 29 having formed integrally therewith valve pistons 30, 31 and 32. A valve chamber 33 is formed between the valve piston 30 and the left-hand end cap of the valve 25. A valve chamber 34 is formed between the valve pistons 30 and 31. A valve chamber 35 is formed between the valve pistons 31 and 32 and a valve chamber 36 is formed between the valve piston 32 and the right-hand end cap of the valve 25. Fluid under pressure from the pump 22 is forced through the pipe 23 and the pipe or passage 24 into the valve chamber 34, between the valve pistons 30 and 31, and passes outwardly through a pipe 39 into a passage 40 formed within the bracket 18, through the hollow piston rod 16 and piston 14, into a cylinder chamber 41, to cause the cylinder 12 and the table 11 to move in a direction toward the right (Fig. 1). During movement of the table 11 toward the right, fluid within a cylinder chamber 42 is exhausted through the piston 13, the hollow piston rod 15,

a passage 43 formed within the bracket 17, and through a pipe 44 into the valve chamber 35 located between the valve pistons 31 and 32, and out through a pipe 45 which returns exhaust fluid through a pipe 46 into the reservoir 20.

A speed control valve 50 (Fig. 1) is preferably formed integral with the table reversing valve 25. As illustrated in the diagram (Fig. 1), the valve is shown as a separate valve unit. The valve 50 is preferably located in the exhaust side of the system so as to maintain a uniform pressure on the operative side of the main cylinder. The valve 50 is preferably connected between the pipes 45 and 46 so as to control the fluid exhausting from the table reversing valve 25. The valve 50 comprises a valve stem 51 which is provided with valve pistons 52, 53 and 54. The valve piston 52 is provided with a V-shaped notch 55 which serves as a V-port. In the position illustrated in Fig. 1, the V-port 55 is located in an operative position opposite the port at the end of the pipe 45 which throttles fluid flowing either from the valve chamber 34 or 35, depending upon the position of the valve 25. The passage or exhaust pipe 46 is operatively connected to convey fluid exhausting through the V-port 55 from the throttle valve 50 into the reservoir 20 so as to control the speed of movement of the table 11.

The throttle valve 50 is arranged so that it may be moved longitudinally and is provided with an actuating knob 59 on the front end of the valve stem 51 which facilitates either an endwise or a rotary movement of the valve stem 51. A rotary movement of the valve stem 51, in the position illustrated in Fig. 1, causes the V-port 55 to vary the exhaust aperture whereby fluid exhausting from the pipe 45 may pass through into the exhaust pipe 46 and serve precisely to adjust and to regulate the exhaust of fluid from the system and thereby provide a fine and precise regulation of the table speed.

In order that the valve piston 52 together with its V-port 55 may be maintained in the desired adjusted position so as to enable the table 11 to be stopped and started as desired, without changing the speed adjustment, a serrated or notched portion 60 is provided which is formed integral with the valve stem 51. A spring-pressed, arrow-pointed detent 61 is carried by the valve casing 50 so that when the knob 59 is rotated to adjust the valve piston 52 to produce the desired and predetermined table speed, the detent 61 engages notches in the serrated portion 60 and serves to hold the valve piston 52 and the V-port 55 in its adjusted rotary position so as to permit longitudinal or axial movement of the valve stem 51 by means of the control knob 59 to start or stop the table movement without upsetting the speed adjustment of the valve 50.

If it is desired to stop the table movement, the knob 59 is moved toward the right (Fig. 1), which movement causes the valve stem 51 together with the V-port 55 also to move toward the right so that the V-port 55 is moved out of line with the port at the end of the pipe 45, thus preventing any exhaust of fluid from the table reciprocating cylinder 12 and thus holding the table 11 in a stopped position.

In order to facilitate a manual traversing movement of the table 11 by any of the old and well known table traverse mechanisms (not shown), it is desirable to provide a fluid by-pass in the hydraulic system whereby fluid may

readily pass from the cylinder chamber 41 at one end of the table cylinder 12 to the cylinder chamber 42 at the other end thereof to facilitate an unrestricted manual traversing movement of the table 11. In the preferred construction, a pipe or passage 62 is provided to connect the pipe 44 and end valve chamber 35 with the valve 50. Similarly, a pipe or passage 63 connects the pipe 39 and valve chamber 34 with the valve 50. The 10 pipes or passages 62 and 63 are arranged on opposite sides of the valve 50. When the throttle valve 50 is moved toward the right to close the V-port 55 and thus stop the hydraulic traversing movement of the table 11, a valve chamber 64 located between the valve pistons 53 and 54 is moved into alignment with ports at the ends of the pipes 62 and 63 so that fluid within the cylinder chamber 41 may pass through the passage 40, the pipe 39, the valve chamber 34, the pipe 63, the valve chamber 64, the pipe 62, the valve chamber 35, the pipe 44, and the passage 43, into the cylinder chamber 42, thus providing a direct by-pass of fluid to facilitate a manual traversing movement of the table 11.

25 When the hydraulic movement of the table 11 is stopped, it is desirable to provide suitable means for preventing the building up of pressure within the pipe 23 from the pump 22. In order to overcome this difficulty, an unrestricted by-pass to the reservoir is provided. The throttle valve 50 is provided with a valve chamber 65 which is located between the valve pistons 52 and 53. When the valve 50 is moved toward the right (Fig. 1) to stop the hydraulic movement of the table, the valve chamber 65 is also moved toward the right so that fluid under pressure entering the pipe or passage 24 may pass outwardly through a pipe 66, through the valve chamber 65, and exhaust through the exhaust pipe 46 into the reservoir 20.

Manual table traverse

A manually operable table traverse mechanism is provided, preferably of a multi-speed type, whereby the table may be traversed manually at a comparatively rapid rate to position the table and a work piece supported thereon relative to the grinding wheel, or may be traversed at a relatively slow rate of speed during a grinding wheel truing operation. This mechanism may comprise a manually operable hand wheel 70 which is provided with an enlarged hub 71. The hand wheel 71 is slidably keyed to an input shaft 72 of a speed reduction unit 73.

The speed reduction unit 73 may be any of the well known speed reducing units. The unit illustrated, however, is the well known "heliocentric" speed reduction unit 73, manufactured by the Universal Gear Corporation of Indianapolis, Indiana. The heliocentric unit 73 is rotatably supported in bearings 74 and 75 which are carried by an apron 76. The driven or input shaft 72 of the heliocentric unit 73 carries a pair of eccentrics 101 and 102. A rotatable output or driven shaft 77 is fixedly mounted to a rotatable plunger holder 103 which travels within a stationary internal gear or rack member which is preferably divided into two parts, namely the internal annular racks 104 and 105. The plunger holder 103 travels within the stationary racks 104 and 105 at the rate of one tooth for each rotation of the input shaft 72. The plunger holder 103 is slotted radially and carries a plurality of reciprocable plungers 106 and 107 which are arranged to work into and out of mesh with

the teeth of the stationary internal racks 104 and 105. The racks 104 and 105 are keyed to the casing, having the appearance of an internal ring gear, but with definitely differing tooth shapes, the teeth of the racks 104 and 105 being substantially wedge-shaped. Due to the working contact between the arrow-pointed plungers 106 and 107 and the teeth of the racks 104 and 105, respectively, a combination of sliding and rolling wedge action is obtained, forcing rotation with a minimum friction to the plunger holder 103 and the output or driven shaft 11. The input eccentrics 101 and 102 force the plungers out under load. A pair of retracting rings 108 and 109 ride in notches formed within the plungers 106 and 107, respectively, to hold back on the no load part of the cycle of operation.

A single eccentric or set of plungers and stationary rack may be employed, but for a maximum smoothness of operation and balance of the working parts, a Universal heliocentric reducer is employed, having two eccentrics as illustrated, each of which actuates a set of plungers in operative engagement with a pair of stationary racks. Each set of plungers is timed directly opposite or 180° apart and has a carrying arc of approximately 120°. The total effect is a balanced distribution of driving power over two-thirds of the complete cycle so that a balanced and uniform slow rotation of the output or driven shaft 11 serves to rotate the eccentric or crankpin 88 to oscillate the heads 25 and 27 simultaneously in opposite directions to cooperate with the combined planetary and rotary movements of the lapping wheels 26 and 28 to produce a very slow uniform traversing movement of the work supporting table 11.

The heliocentric unit 13 is provided with an output shaft 11 which has a gear 78 keyed thereon. The gear 78 meshes with a rotatable idler gear 79 which is rotatably supported on a shaft 80. The gear 79 meshes with a gear 81 which is keyed on a rotatable shaft 82. The shaft 82 is journalled in bearings 83 and 84 which are supported in a bracket 85 fixedly mounted on the apron 15. The shaft 82 rotatably supports a gear 86 which meshes with a rack bar 87 depending from the under side of the table 11. The shaft 82 also supports a clutch member 88 which is slidably keyed thereon and which is arranged to be moved into and out of mesh with clutch teeth 89 formed integral with the gear 86. When the clutch 88 is disengaged from the clutch teeth 89, no rotary motion will be imparted between the shaft 82 and the gear 86.

It is desirable that during the hydraulic traverse of the table 11, the hand traverse mechanism be rendered inoperative. In order to accomplish this result, a hydraulically operated mechanism is provided comprising a cylinder 90 having a slidably mounted piston 91 which is arranged to engage and actuate a rock arm 92. The rock arm 92 is pivotally supported by a stud 93 which is in turn fixedly supported on the bracket 85. The upper end of the rock arm 92 is yoke-shaped and is provided with spaced diametrically opposed studs 94 which ride in a groove 95 formed in the periphery of the clutch member 88. A spring 96 interposed between the lower end of the rock arm 92 and a depending projection 97 formed integral with the cylinder 90 normally tends to hold the clutch 88 in engagement with the clutch teeth 89. When the fluid pressure by-pass from the chamber 24 through the pipe 66 to the reservoir 20 is cut off

so that fluid is conveyed through the control valve 25 to the table cylinder 12, fluid under pressure is also passed from the chamber 24 through a pipe 98 into the cylinder 90 to move the piston 91 toward the right (Fig. 4) to disengage the clutch member 88, thus rendering the hand traverse mechanism inoperative. The clutch mechanism and the hydraulic means for operating the same is shown diagrammatically in Fig. 1. Less power is required to operate the clutch 88; consequently the clutch will be disengaged before the table is set in motion.

A clutch mechanism is provided between the hand wheel 10 and the heliocentric unit 13, comprising an internal ring gear 99 which is fixedly mounted to the hub 71 to rotate with the hand wheel 10. A gear 100 of the same pitch diameter as the gear 99 is fixedly mounted to the heliocentric casing 13. When the hand wheel is in the position illustrated in Fig. 4, the ring gear 99 meshing with the gear 100 operatively connects the hand wheel with the housing 73 of the heliocentric unit so that when a rotary motion is imparted to the hand wheel 10, it will rotate the heliocentric unit 13 and transmit a one to one rotation between the hand wheel 10 and the gear 78 which in turn transmits rotation through the clutch parts 88-89 to rotate the gear 86 and thus impart a longitudinal traversing movement to the rack bar 87 and the table 11.

If a slow traversing movement of the table is desired, the hand wheel is moved toward the left (Fig. 4) to disengage the ring gear 99 from the gear 100. A binder or clamping screw 68 is tightened to lock the heliocentric casing 13 relative to the apron 15. In this condition of the parts, any rotary motion of the hand wheel 10 is transmitted through the shaft 12 which operates through the speed reduction unit to impart a slow rotary motion to the output shaft 11 which in turn transmits a rotary motion through the gear mechanism above described and through the clutch parts 88-89 to rotate the gear 86 and thereby transmit a slow traversing movement 45 to the rack bar 87 and the table 11.

Table reverse mechanism

A suitable reversing mechanism is provided to change the direction of movement of the table automatically as desired. In the preferred construction, adjustable table dogs 110 and 111 are adjustably mounted in a T-slot 112 formed in the front edge of the table 11. The dogs 110 and 111 are arranged to engage a stud 113 which is fixedly mounted on the upper end of a reverse control lever 114. The reversing lever 114 is fixedly mounted on the forward end of a rock shaft 115 which is journalled in a bearing 116 formed in an apron 117 which is in turn fixedly mounted on the base 10 of the machine. A rock arm 118 is fixedly mounted on the inner end of the shaft 115 (Fig. 2). The upper end of the rock arm 114 is formed as a yoke-shaped member 119 having diametrically opposed studs 120 and 121 which engage a groove 122 formed in a spool-shaped member 123. The spool-shaped member 123 is fixedly mounted on the end of the valve stem 29 of the table reversing valve 25. It will be readily apparent from the foregoing disclosure that when the reversing lever 114 is moved in either direction by either the table dog 110 or 111, a rocking motion will be imparted to the shaft 115 which will in turn transmit a rocking motion through the yoke-shaped member 119

to the studs 120 and 121 to shift the valve stem 29.

It should be noted that the valve pistons 30 and 32 of the control valve 25 are wide faced pistons and are preferably so arranged that when the valve stem 29 is moved by motion of the table, the pistons 30 and 32 will move only a sufficient distance so that fluid entering the chamber or passage 24 is cut off by both the valve piston 30 and valve piston 32 so that no fluid under pressure can pass through either the pipe 39 or 44 to the table cylinder 12, thus bringing the table 11 to a stop.

Table dwell control

In order to obtain a dwell of a predetermined extent at the ends of the table stroke, a suitable hydraulically operated, electrically controlled mechanism is provided to control the shifting movement of the valve 25 from a neutral position into the reverse position. A pipe 125 is connected between the pressure pipe 23 and an electrically controlled, normally closed valve 126. The valve 126 is a piston type valve comprising a valve stem 127 having pistons 128 and 129 formed integrally therewith. The valve 126 is normally held in a left-hand end position (Fig. 1) by means of a compression spring 130 which surrounds the valve stem 127 and is interposed between the piston 129 and the end cap at the right-hand end of the valve 126. A solenoid 131 is operatively connected so that when energized it will shift the valve stem 127 toward the right (Fig. 1) so that fluid under pressure passing through the pipe 125 enters a valve chamber 132 located between the valve pistons 128 and 129 and passes outwardly through a pipe 133. The pipe 133 is connected with the end chamber 33 of the table control valve 25. In the position of the parts as illustrated in Fig. 1, fluid may exhaust through the pipe 133, the valve chamber 113, and through an exhaust pipe 134 into the reservoir 20.

Similarly, the pipe 125 is connected with an electrically controlled, normally closed valve 136. The valve 136 is substantially the same in construction as the valve 126 and comprises a valve stem 137 having valve pistons 138 and 139 formed integrally therewith. A compression spring 140 serves normally to hold the valve stem 137 in its right-hand end position (Fig. 1). An electric solenoid 141 is operatively connected to the valve stem 137 and is arranged so that when energized it will shift the valve stem 137 toward the left so that fluid under pressure passing through the pipe 125 will enter a valve chamber 142 located between the valve pistons 138 and 139 and pass outwardly through a pipe 143. The pipe 143 is connected with the end chamber 36 of the table control valve 25 so that when fluid is admitted through the pipe 123 into the chamber 36, the table control valve 25 will be moved rapidly under the influence of fluid under pressure into its extreme left-hand end position (Fig. 1).

An electrically operated control mechanism is provided which is preferably actuated and controlled by and in timed relation with the movement of the table reversing lever. An electrical time delay relay 145 is provided for controlling the solenoids 131 and 141. The time relay 145 may be any of the standard electric time relays such as, for example, the Microflex time relay manufactured by Eagle Signal Corp. of Moline, Illinois.

The rock arm 118 which is supported on the

inner end of the rock shaft 115 (Fig. 2) has a downwardly extending arm 148 which is fixedly mounted relative to the shaft 115 and moves with the table reversing lever 114. The lower end of the arm 148 is provided with a roller 147. The roller 147 is arranged to engage a cam 148 which is carried at one end of a rock arm 149. The rock arm 149 is pivotally mounted on a stud 150. The movement of the rock arm 149 in a counterclockwise direction is limited by a stud 151 which is fixed relative to the base of the machine. The arm 149 supports an adjustable screw 152 which is arranged to engage the actuating plunger 153 of a normally open limit switch 154. The limit switch 154 is operatively connected with the time relay 145 so that when the reversing lever is shifted, the roller 147 will engage the cam 148 and rock the rock arm 149 in a clockwise direction so as to close the limit switch 154 and start the time relay 145.

A normally closed limit switch 155 is mounted on the frame 156 and is provided with an actuating plunger 157. The plunger 157 is arranged to be actuated either by a rock arm 158 which is pivotally supported by a stud 159 or by a rock arm 160 which is pivotally supported on a stud 161. The rock arms 158 and 160 are provided with upwardly extending projections 162 and 163, respectively. The projecting bosses 162 and 163 support a pair of screws 164 and 165, respectively, which are arranged in the path of the actuating roller 147 at the lower end of the lever 146 which moves with the reversing lever 114. The inner ends of the rock arms 158 and 160 are arranged in the path of the actuating plunger 157 of the limit switch 155. When the reversing lever 114 is shifted into its reverse position in either direction, the roller 147 engages either the screw 164 or the screw 165 and rocks either the arm 158 in a counterclockwise direction or the arm 160 in a clockwise direction to produce an upward movement of the plunger 157 so as to open the switch 155 at the end of the stroke of the reversing lever 114. By adjusting the screws 164 and 165, the time of opening the limit switch 155 at each end of the movement of the reverse lever 114 may be varied as desired.

In order that the time relay 145 may operate at each end of the table stroke respectively to control the solenoids 131 and 141, an electric switch mechanism is provided including a reversing switch 170 which is actuated by and in timed relation with the movement of the reversing lever 114. The downwardly extending arm 148 is provided with a rearwardly projecting stud 171 (Fig. 2) which is arranged to engage a V-shaped notch formed in the upper end of a rock arm 172 which in turn serves as an actuating lever for the reversing switch 170. In Fig. 1 the switch 170 has been illustrated directly in back of the reversing lever 114 and has also been shown diagrammatically in the same view so as to clarify the electrical wiring connections therewith. A magnetic switch 173 is interposed between the reversing switch 170 and the solenoid 131 to control the setting in motion of the time relay 145 to energize the solenoid 131. Similarly, a magnetic switch 174 is interposed between the reversing switch 170 and the solenoid 141 so as to render the time relay 145 operative to control the energization of the solenoid 141 when the table 11 is at the other end of its reciprocatory stroke.

Operation

The operation of the table traversing and re-

ciprocating mechanism will be readily apparent from the foregoing disclosure. Assuming the valves and switches are positioned as illustrated in Fig. 1, fluid under pressure from the pump 22 passes through the pipe 23 into the passage 24 and through the valve chamber 34, out through the pipe 39, into the cylinder chamber 41, to cause the cylinder 12 and table 11 to move toward the right (Fig. 1). The movement of the table 11 toward the right continues until the table reversing dog 110 engages the stud 113 on the reversing lever 114 and rocks the lever 114 in a clockwise direction (Fig. 1). The table 11 continues its movement toward the right until the table dog 110 moves the reversing lever 114 a sufficient distance so that valve piston 30 covers the port at the right-hand end of the passage 24 (the valve piston 32 already covering the port at the right-hand end of the passage 24), which movement stops the movement of the table 11 by cutting off fluid under pressure from both the pipes 39 and 44. During the clockwise shifting movement of the reversing lever 114, the roller 147 engages the cam 148 and rocks the rock arm 149 in a clockwise direction. This movement of the arm 149 depresses the plunger 153 to close the normally open limit switch 154. The closing of the limit switch 154 serves through the electrical connections diagrammatically illustrated in Fig. 1 to set in motion the electrical time delay relay 145.

The table 11 is held in a stationary position for a predetermined time interval as determined by the setting of the time relay 145. After the time interval has elapsed, the time relay 145 closes the magnetic switch 173 which instantaneously energizes the solenoid 131 to shift the valve 126 toward the right (Fig. 1), which movement opens the valve so that fluid under pressure direct from the pump 22 may pass through the pipe 125, the valve chamber 132, and the pipe 133, into the end chamber 33 of the table control valve 25 to rapidly shift the table control valve stem 29 together with the reversing lever 114 toward the right (Fig. 1) to shift the valve from a neutral position into the reverse position so that fluid under pressure from the pump will pass through the pipe 44 into the cylinder chamber 42 to start the table 11 moving in the reverse direction.

As the lever 114 swings in a clockwise direction rapidly into the reverse position, the roller 147 engages the screw 164 and rocks the rock arm 158 in a counterclockwise direction on its supporting stud 159, which movement raises the plunger 157 to open the normally closed limit switch 155 which opens a circuit to deenergize and open the magnetic switch 173. The opening of the magnetic switch 173 deenergizes the solenoid 131, thus allowing a released compression of the spring 130 to return the valve 126 to the position illustrated in Fig. 1. At the same time the magnetic switch 173 opens, the time relay 145 automatically resets itself ready for the next operation. The magnetic switch 173 is operatively connected in such a manner that when the switch 173 is closed by the closing of the normally open limit switch 154, the switch 173 will remain closed even though the reversing switch 170 is shifted during the movement of the reversing lever 114 toward and into its reverse position.

As soon as the reversing valve 25 has completed its reverse movement, fluid under pressure from the pump 22 passing through the

pipe 23 and the passage 24 will pass through the valve chamber 35, the pipe 44, into the cylinder chamber 42, to cause the cylinder 12 and table 11 to start its traversing movement toward the left (Fig. 1). The table 11 continues its movement toward the left until the table dog 111 engages the stud 113 on the reversing lever 114 and moves the reversing lever 114 in a counterclockwise direction, which movement shifts the reversing valve 25 so that the valve pistons 30 and 32 cut off the admission of fluid under pressure from the passage 24 to stop and hold the table 11 stationary for a predetermined period of dwell as governed by the setting of the electrical time delay relay 145.

During the shifting movement of the reversing lever 114 in a counterclockwise direction, the roller 147 again engages and moves the cam 148 to depress the rock arm 149, thus closing the normally open limit switch 154 which closes a circuit to close the magnetic switch 174 and at the same time starts the time relay 145 in motion. After a predetermined time interval, the electric time relay 145 energizes the solenoid 141 to shift the valve 136 toward the left (Fig. 1) so that fluid under pressure from the pipe 125 may pass through the valve chamber 142 and through the pipe 143 into the end chamber 36 of the main control valve 25 rapidly to shift the control valve stem 29 toward the right into the position illustrated in Fig. 1, thus reversing the direction of flow of fluid under pressure to the table cylinder 12. When the reversing lever 114 has completed its movement in a counterclockwise direction, the roller 147 engages the screw 165 to rock the arm 160 in a clockwise direction on its supporting stud 161 as a pivot to raise the plunger 157, thus opening the normally closed switch 155 to open the magnetic switch 174, thereby deenergizing the solenoid 121 so that the released compression of the spring 140 shifts the valve 136 into the position illustrated in Fig. 1. At the same time the switch 174 opens, the electric time relay 145 resets automatically so that it is ready to function at the next reversal in direction of the movement of the table 11.

When it is desired to stop the hydraulic reciprocation of the table 11, the knob 59 is moved toward the right (Fig. 1) to shut off the exhaust of fluid through the pipe 45 and thus stop the table movement. This movement of the valve 50 opens the valve chamber 65 connecting the pipe 66 with the pipe 46 so that fluid under pressure from the pump 22 is returned directly into the reservoir 20. This direct by-pass of the fluid releases the compression of the spring 96 which automatically serves to engage the clutch member 88 with the clutch teeth 89, thus automatically rendering the manually operable traverse mechanism operative.

If a rapid manual traversing movement of the table 11 is desired, the clamping screw 68 is released, thus permitting rotation of the housing 73 of the speed reduction unit. A rotary motion of the hand wheel 70 will then be transmitted to rotate the entire speed reduction unit on its supporting bearings 74 and 75 to transmit a rotary motion to the table rack 87 to move the table 11 longitudinally at a comparatively fast speed. If a slow traversing movement of the table is desired, the clamping screw 68 is tightened to hold the housing 73 of the speed reduction unit against rotation and the hand wheel 70 is moved toward the left (Fig. 4) to

disengage the clutch gears 88-100. In this position of the parts, rotation of the hand wheel 76 will transmit a rotary motion through the input shaft 12 of the speed reduction unit 13 which will transmit a very slow rotation to the output shaft 11. The output shaft 11 will transmit this slow rotary motion through the gear mechanism and clutch mechanism above described to rotate the gear 88 slowly so as to impart a slow traversing movement to the rack 10 bar 87 and the table 11.

When it is desired to again start the hydraulic reciprocating movement of the table 11, the knob 89 is again moved toward the left (Fig. 1) to position the valve 50, as illustrated in Fig. 1, so that fluid under pressure from the pump passing into passage 24 passes through the valve 25 and either the pipe 39 or the pipe 44 to the table cylinder. At the same time, fluid under pressure passes through the pipe 88 into the cylinder 88 to move the clutch member 88 out of engagement with the clutch teeth 89, thus rendering the hand traversing mechanism inoperative.

It will thus be seen that there has been provided by this invention apparatus in which the various objects hereinabove set forth together with many thoroughly practical advantages are successfully achieved. As many possible embodiments may be made of the above invention and as many changes might be made in the embodiment above set forth, it is to be understood that all matter hereinbefore set forth or shown in the accompanying drawings is to be interpreted as illustrative and not in a limiting sense.

I claim:

1. In a grinding machine, a longitudinally movable table, means including a piston and cylinder to reciprocate said table, a reversing valve therefor, means including a table actuated lever to move said valve to a central or neutral position to stop the table, an end chamber formed at each end of said reversing valve, a pair of control valves to control the admission of fluid under pressure to said end chambers respectively, and means including an adjustable time delay relay which is rendered operative by movement of said lever, said time relay being operatively connected to open one of said control valves after a predetermined time interval to admit fluid under pressure to one of said end chambers rapidly to shift the reversing valve into a reverse position.

2. In a grinding machine, a longitudinally movable table, means including a piston and cylinder to reciprocate said table, a reversing valve therefor, means including a table actuated lever to move said valve to a central or neutral position to stop the table, an end chamber formed at each end of said reversing valve, a pair of solenoid valves to control the admission of fluid under pressure to said end chambers respectively, and means including an adjustable electrical time delay relay which is rendered operative by movement of said lever, said time relay being operatively connected to open one of said solenoid valves after a predetermined time interval to admit fluid under pressure to one of said end chambers rapidly to shift the reversing valve into a reverse position.

3. In a grinding machine, a longitudinally movable table, means including a piston and cylinder to reciprocate said table, a reversing valve therefor, a supply of fluid under pressure, means including a control lever to move said valve to a central or neutral position to stop said table, end

chambers formed at opposite ends of said reversing valve, a pair of control valves which are normally closed to the supply of fluid under pressure but open to exhaust fluid from said end chambers which are arranged to control the admission of fluid under pressure to said end chambers respectively, and means including an adjustable time delay relay which is rendered operative by said control lever, said time relay being operatively connected to actuate one of said control valves to admit fluid under pressure to one of said end chambers rapidly to shift the reversing valve into a reverse position.

4. In a grinding machine, a longitudinally movable table, means including a piston and cylinder to reciprocate said table, a reversing valve therefor, end chambers formed at opposite ends of said reversing valve, a supply of fluid under pressure, means including a control lever to actuate said valve, a pair of independent electrically controlled valves, one of said valves being connected in a pipe line between the fluid pressure supply and an end chamber at one end of the reversing valve, the other of said valves being connected in a second pipe line between said fluid pressure supply and a chamber at the other end of the reversing valve for controlling the shifting of the valve into reverse positions, an adjustable time delay relay which is rendered operative by said control lever, and means actuated by said lever to render one of said electrically controlled valves operative when the control lever is moved in one direction and to render the other control valve operative when the lever is moved in the opposite direction.

5. In a grinding machine, a longitudinally movable table, means including a piston and cylinder to reciprocate said table, a reversing valve therefor, end chambers formed at opposite ends of said reversing valve, a supply of fluid under pressure, means including a control lever to actuate said valve, a pair of independent electrically controlled valves, one of said valves being connected in a pipe line between the fluid pressure supply and an end chamber at one end of the reversing valve, the other of said valves being connected in a second pipe line between said supply of fluid under pressure and a chamber at the other end of the reversing valve for controlling the shifting of the valve into reverse positions, an adjustable time delay relay which is rendered operative by said control lever, means actuated by said lever to render one of said electrically controlled valves operative when the control lever is moved in one direction and to render the other control valve operative when the lever is moved in the opposite direction, and an electrically operated time delay mechanism actuated by and in timed relation with the control lever to open one of said valves after a predetermined period of dwell to admit fluid under pressure to the end chamber of the reversing valve.

6. In a grinding machine, a longitudinally movable table, means including a piston and cylinder to reciprocate said table, a reversing valve therefor, a supply of fluid under pressure, means including a control lever to actuate said valve to stop the table movement in either direction, a pair of independent solenoid valves, one of which is connected in a direct pipe line between the supply of fluid under pressure and an end chamber at one end of the reversing valve and the other of which is connected in a direct pipe line from the supply of fluid under pressure to

the other end of the reversing valve to control the shifting of the reversing valve into its reverse position, an adjustable time delay relay which is rendered operative by the shifting of said control lever, said time relay being operatively connected to open one of said solenoid valves after a predetermined time interval to pass fluid directly from the supply of fluid under pressure into the end chamber of the reversing valve rapidly to shift it into the reverse position, and means including a switch actuated by the reversing lever to render one of the solenoid valves operative when the lever is moved in one direction and to render the other solenoid valve operative when the lever is moved in the opposite direction.

7. In a grinding machine, a longitudinally reciprocable table, means including a piston and cylinder operatively connected to reciprocate said table, a reversing valve which is arranged to admit fluid under pressure to either end of said cylinder, a pair of adjustable dogs on said table, means including a control lever operatively connected to move said valve to a central or neutral position when acted upon by one of said dogs to stop the table movement, a pair of independent solenoid valves operatively connected with an end chamber at each end of the reversing valve, said solenoid valves being connected in a direct pipe line from the supply of fluid under pressure to the end chambers at respective ends of the reversing valve, said solenoid valves serving to control the admission of fluid under pressure to the end chambers after a predetermined time interval has elapsed, and means including a time delay relay which is set in motion in timed relation with the movement of the reverse lever to open the solenoid valve and rapidly admit fluid under pressure to complete the reverse movement of said valve.

8. In a grinding machine, a longitudinally reciprocable table, means including a piston and cylinder operatively connected to reciprocate said table, a supply of fluid under pressure, a reversing valve which is arranged to admit fluid under pressure to either end of said cylinder, a pair of adjustable dogs on said table, means including a control lever operatively connected to move said valve to a central or neutral position

5 to cut off fluid under pressure to both ends of the table and thereby stop the table movement when acted upon by one of said dogs, a pair of independent solenoid valves operatively connected with an end chamber at each end of the reversing valve, each of said solenoid valves being connected by pipes directly with the supply of fluid under pressure, a limit switch, an adjustable connection between said lever and a limit switch, and an electrical time delay relay which is set in motion by said limit switch, said time delay relay being operatively connected to energize one of said solenoid valves to open the pipe line to pass fluid under pressure directly from the supply of fluid under pressure to an end chamber of the reversing valve rapidly to shift the valve into its reverse position.

9. In a grinding machine, a longitudinally reciprocable table, means including a piston and cylinder operatively connected to reciprocate said table, a supply of fluid under pressure, a reversing valve which is arranged to admit fluid under pressure to either end of said cylinder, a pair of adjustable dogs on said table, means including a control lever operatively connected to move said valve to a central or neutral position to cut off fluid under pressure to both ends of the table and thereby stop the table movement when acted upon by one of said dogs, a pair of independent solenoid valves operatively connected with an end chamber at each end of the reversing valve, each of said solenoid valves being connected by pipes directly with the supply of fluid under pressure, a limit switch, an adjustable connection between said lever and a limit switch, an electrical time delay relay which is set in motion by said limit switch, said time delay relay being operatively connected to energize one of said solenoid valves to open the pipe line to pass fluid under pressure directly from the supply of fluid under pressure to an end chamber of the reversing valve rapidly to shift the valve into its reverse position, and means including a second switch actuated by the control lever at the ends of its stroke to deenergize the solenoid and break the circuit to allow the relay to reset itself for the next operation.

JOHN I. GARSIDE.
